Patented Jan. 10, 1922.

Inventor

George A. Hertlein

UNITED STATES PATENT OFFICE.

GEORGE A. HERTLEIN, OF MAYWOOD, ILLINOIS.

AIR GUN.

1,403,029.

Specification of Letters Patent. Patented Jan. 10, 1922.

Application filed July 26, 1921. Serial No. 437,612.

To all whom it may concern:

Be it known that I, GEORGE A. HERTLEIN, a citizen of the United States, residing at Maywood, in the county of Cook and State 5 of Illinois, have invented certain new and useful Improvements in Air Guns, of which the following is a specification.

This invention relates to air guns and has for its object to provide a gun having novel 10 means whereby the same may be cocked or set for use with a minimum of effort on the part of the operator.

A further object of the invention is to provide an air gun which will not go off accidentally and which is therefore extremely 15 safe in use.

A further object of the invention is to provide a gun of the class described which is of highly simplified construction, durable in 20 use and cheap to manufacture.

Other objects and advantages of the invention will be apparent during the course of the following description.

Figure 1 is a detail longitudinal sectional view through the gun.

Figure 2 is a vertical transverse sectional view taken on line 2—2 of Figure 1.

Figure 3 is a group perspective of a plunger and associated elements.

In the drawing wherein for the purpose of illustration is shown a preferred embodiment of the invention the numeral 5 designates a case which is provided with a chamber 6 forming a housing for the operating parts for the gun. As illustrated in Figure 1 a barrel 8 is secured to the case 5 by means of straps 9 and slidably receives a piston 10 having a rearwardly directed piston rod 11 surrounded by a coiled spring 12. The forward end of the coiled spring 12 contacts with the rear side of the plunger 10 while the rear end of the spring contacts with a transversely extending partition 14. Nuts 15 are threaded on the plunger rod 11 45 on opposite sides of the piston 10 and may be adjusted to vary the position of the piston 10 with relation to the plunger rod.

The rear end of the piston rod 11 is provided with a downwardly extended dog 18 secured thereon by means of a nut 19. When the dog 18 is drawn rearwardly by means to be later described the coiled spring 12 is contracted and the piston 10 is set for operation. When the dog 18 is released the 55 piston 10 immediately moves forwardly to project or discharge a projectile 20 of any

suitable size. When the dog 18 moves forwardly, the same engages a cushioning washer 23 secured on the plunger rod rearwardly of a nut 21 which is threaded on 60 the plunger rod. A spacing tube 22 is confined between the partition 15 and the nut 21.

The piston rod 11 is drawn rearwardly by means of an arm 24 having its rear end extended angularly and bifurcated as indicated at 25 so as to slidably receive the tube 22 and to extend on opposite sides of the cushioning washer 23. When the arm 24 is drawn rearwardly the angularly extended 65 end portion of the same engages the dog 18 and thereby retracts the piston 10. The forward portion of the arm 24 is extended angularly in the opposite direction from the extended end portion 25 as indicated at 27 70 and has pivotal connection with the rearwardly extending link 28 connected to the forward end of a lever 30 as indicated at 31. With reference to Figure 1 it will be observed that the forward portion of the setting lever 30 is curved upwardly and forwardly so that when the rearwardly extending handle 33 of the same is drawn downwardly and forwardly about the pivot element 34 the link 28 will be drawn rearwardly for cocking the gun. 80

The setting lever 30 is provided with a curved portion 36 which constitutes a guard for the trigger 37 connected to a trip 38 adapted to engage the lower portion of the 90 dog 18 whereby to hold the plunger 10 in a retracted position. A coiled spring 39 is confined between the laterally extending arm 40 of the plunger and the rear portion of a guide 41 and acts to normally hold the trip 95 38 in engagement with the plunger 18 when the piston is retracted.

The longitudinally movable arm 24 is supported for sliding movement on the guide 41 and the lower terminal portion of the arm 100 18 is also received within said guide.

In carrying out the invention the gun may be provided with a stock 45 and with an extension 46 on the forward end of the barrel. Should the projectile 20 be inserted 105 into the barrel prior to cocking air may be admitted into the barrel through a valve opening 47 which is surrounded by a cage 48 within which is arranged a ball valve 49. With reference to Figure 1 it will be observed that the ball valve 49 is normally held in its seated position by means of a

coiled spring, the said coiled spring being confined between the ball valve and the lower side of the barrel. When the piston 10 is retracted the ball valve 49 is unseated to admit a quantity of air to be supplied to the barrel. In operation the lever 30 is operated to draw the arm 24 rearwardly for the purpose of cocking the gun. When it is desired to fire the gun it is merely necessary to pull on the trigger 37 whereupon the dog 18 is released to permit of the advancement of the piston 10. A projectile may be readily inserted into the gun by any suitable means and by reason of the construction described it will be discharged at a high velocity.

Having thus described my invention, what is claimed is:

1. A gun of the class described comprising a casing, a barrel connected to the casing, a piston arranged in the barrel and having a rearwardly directed piston rod, a partition traversing the barrel, a coiled spring confined between said partition and the piston for advancing the piston, a downwardly extending dog secured to the rear end of said piston rod, a tripping device engaged with said dog and having a trigger, a longitudinally movable arm having its rear portion extended angularly and bifurcated to straddle said piston rod, and to engage said dog, a link pivotally connected to the forward portion of said arm, a lever pivoted intermediate its ends and having pivotal connection with the rear portion of said link whereby to crank said gun, a cushioning washer secured on said piston rod in advance of said dog and adapted to engage the angularly extending end portion of said arm, and a guide slidably receiving said arm and said dog.
2. A gun of the class described comprising a casing, a barrel connected to the casing, a piston arranged in the barrel and having a rearwardly directed piston rod, a partition traversing the barrel, a coiled spring confined between said partition and the piston for advancing the piston, a downwardly extending dog secured to the rear end of said piston rod, a tripping device engaged with said dog and having a trigger, a longitudinally movable arm having its rear portion extended angularly and bifurcated to straddle said piston rod, and to engage said dog, a link pivotally connected to the forward portion of said arm, a lever pivoted intermediate its ends and having pivotal connection with the rear portion of said link whereby to crank said gun, a cushioning washer secured on said piston rod in advance of said dog and adapted to engage the angularly extending end portion of said arm, and a guide slidably receiving said arm and said dog, and a check valve admitting air to said barrel.

tending dog secured to the rear end of said piston rod, a tripping device engaged with said dog and having a trigger, a longitudinally movable arm having its rear portion 50 extended angularly and bifurcated to straddle said piston rod, and to engage said dog, a link pivotally connected to the forward portion of said arm, a lever pivoted intermediate its ends and having pivotal connection with the rear portion of said link whereby to crank said gun, a cushioning washer secured on said piston rod in advance of said dog and adapted to engage the angularly extending end portion of said arm, and a 60 guide slidably receiving said arm and said dog.

3. A gun of the class described comprising a casing, a barrel connected to the casing, a piston arranged in the barrel and having a rearwardly directed piston rod, a partition traversing the barrel, a coiled spring confined between said partition and the piston for advancing the piston, a downwardly extending dog secured to the rear end of said 65 piston rod, a tripping device engaged with said dog and having a trigger, a longitudinally movable arm having its rear portion extended angularly and bifurcated to straddle said piston rod, and to engage said 70 dog, a link pivotally connected to the forward portion of said arm, a lever pivoted intermediate its ends and having pivotal connection with the rear portion of said link whereby to crank said gun, a cushioning 75 washer secured on said piston rod in advance of said dog and adapted to engage the angularly extending end portion of said arm, a guide slidably receiving said arm and said 80 dog, and a check valve admitting air to said 85 barrel.

In testimony whereof, I have affixed my signature in the presence of two witnesses.

GEORGE A. HERTLEIN.
